JAMES K. GREER AND CASKIE CURTRIGHT, OF PARIS, MISSOURI.

AUTOMATIC AIR-GAGE.

1,334,897.

Specification of Letters Patent. Patented Mar. 23, 1920.

Application filed April 11, 1919. Serial No. 289,219.

To all whom it may concern:

Be it known that we, JAMES K. GREER and CASKIE CURTRIGHT, citizens of the United States, residing at Paris, in the county of Monroe and State of Missouri, have invented new and useful Improvements in Automatic Air-Gages, of which the following is a specification.

This invention relates to automatic air gages, and has for its object the provision of a gage particularly adapted for use in garages or the like where pneumatic tires are filled with air, the construction of the device being such that a predetermined pressure may be supplied to the tire, and such that when such pressure has been reached a valve will be automatically closed for stopping the flow of air.

An important object is the provision of a device of this character which is provided with an indicating hand which may be set at the desired place upon a series of indicia indicating various air pressures, movement of this hand compressing a spring which tends to close the control valve, this spring being released by a trigger disengaged from retaining means upon the pressure in the tire or other device reaching the predetermined amount.

A further object is the provision of a device of this character which will be automatic and efficient in action, which is not likely to become deranged, which may be easily operated, and which will be durable.

With the above and other objects and advantages in view, such as comparative simplicity, and the general improvement in the art, the invention consists in the details of construction to be hereinafter more fully described and claimed, and illustrated in the accompanying drawings, in which—

Figure 1 is a front elevation of the device,

Fig. 2 is a longitudinal sectional view showing the parts arranged with the control valve in closed position,

Fig. 3 is a similar view with the control valve in open position,

Fig. 4 is a horizontal sectional view taken through the actuating gear, and

Fig. 5 is a longitudinal sectional view taken at right angles to the plane of Figs. 2 and 3, showing the trigger release mechanism.

Fig. 6 is a sectional perspective view of the tire valve engaging nipple.

Referring more particularly to the draw-

ings, the numeral 10 designates a preferably rectangular casing which may preferably be secured upon the wall at a convenient height to be within reach of the operator. The 60 casing 10 is provided with a cover 11 upon which is arranged an arcuate series of indicia 12 indicating pressure in pounds. Journaled through the casing 10 and cover 11 is a horizontal shaft 13 which has its 65 forward end provided with an indicating hand 14 movable over the indicia 12. Within the casing 10 the shaft 13 has secured thereon a gear 15.

Extending into the casing 10 is a pipe 16 70 which leads from any suitable source of compressed air supply, not shown, and which communicates with the lower end of a vertically disposed housing 17 disposed within the casing 10 and having connected 75 therewith a laterally extending pipe 18 which extends beyond the casing 10 at the side opposite to that provided with the pipe 16 and which is adapted to have connected therewith a suitable flexible hose 18a, such 80 as is used for conducting compressed air to tires.

The upper end of the housing 17 is closed and provided with a central opening through which is slidable a rack bar 20 85 meshing with the gear 15 and forming the stem of a plunger head 21. A coil spring 22 surrounds the rack bar 20 and abuts at one end against the closed upper end of the housing 17 and at its other end against the 90 plunger head 21. Formed within the junction of the pipe 16 with the housing 17 is an upwardly extending nipple 23, the upper 95 end of which forms a valve seat upon which is disposed a valve 24 having a stem 25 guidably received within a spider 26 disposed within the lower portion of the housing 17. A coil spring 27 surrounds the nipple 23 and engages the valve 24 for normally tending to unseat the valve 24.

Secured upon the upper end of the rack bar 20 is a plate 28 adapted for vertical movement with the rack bar 20 and engaged upon guides 29 secured within the casing 10. Also secured within the casing 10 is a vertically extending bar 30 having one edge provided with ratchet teeth 31 adapted for engagement by a spring trigger 32 carried by the rear edge of the plate 28. The spring trigger 32 normally engages the teeth 31 105 which are so arranged that the trigger may have unrestricted upward movement along

the bar 30 but will be prevented by the teeth 31 from having downward movement.

Also disposed within the casing 10 is a housing 19 which has its upper end closed 5 and provided with a central opening through which is slidable a stem 33 carrying at its lower end a plunger head 34 which is normally urged downwardly into a valve seat 35 within the housing 19 by a coil spring 10 36 which abuts against the plunger head 34 and against the closed upper end of the housing 19. The upper extremity of the stem 33 is beveled, as shown at 37 and is engageable upon upward movement thereof 15 with the trigger 32 for moving the trigger 32 away from the plate 28 and out of engagement with the ratchet teeth 31.

Secured upon and communicating with the lower end of the housing 19 is a pipe 38 to 20 which is connected a flexible hose 39 which extends parallel with and may be secured to the hose 18^a so that these two hose may be handled as one.

Adapted for use with our device is a nipple 25 40 which comprises a body 41 provided with a bore 42 which is provided at its open end with a rubber washer 43. This nipple is engageable upon the valve stem of a tire and the washer 43 is for the purpose of effecting an air-tight fit therewith. Formed 30 within the bore 42 is a valve seat 44 upon which is disposed a valve 45 having a stem 46 extending through a spider 47 disposed adjacent the open end of the nipple. Secured 35 upon the stem 46 is a washer or collar 48 and surrounding the stem is a spring 49 which abuts at one end against the valve seat 44 and at its other end against the washer 48 whereby the valve 45 will be retained 40 normally seated. Formed upon the body 41 is an extension 50 provided with a bore 60 communicating with the bore 42 above the valve 45 with reference to its seat 44. This body 41 is further provided 45 with a nipple portion 61 upon which is engaged the rubber hose 39 leading to the pipe 38 communicating with the lower end of the housing 19.

In the operation of the device the operator 50 grasps the nipple 40 and places the same over the valve stem of the tire to be inflated, the end of the valve stem engaging against and making air-tight connection with the washer 43, and the stem of the valve engaging 55 and being nested by the stem 46 of the valve 45 and also unseating the valve 45. The operator then grasps the indicating hand 14 and moves the same so that its point will lie upon the desired one of the indicia 60 12 upon the cover 11 of the casing. This movement of the hand 14 results in partial rotation of the gear 15 which will consequently elevate the rack bar 20 a certain distance. This upward movement of the bar 20 releases pressure of the plunger head 65

21 upon the valve 24 and compresses the spring 22. The plate 28 is of course carried upwardly by the bar 20, the trigger riding over the teeth 31 on the bar 30 until the stem 25 and plate 28 cease to move, 70 whereupon downward movement of the plate 28 will be prevented by engagement of the trigger 32 with a tooth 31. At this time it is understood that the plunger head 34 is in engagement with the valve seat 35 75 in the housing 19. The moment that the handle 14 is moved and the rack bar 20 elevated, the pressure of the spring 27 surrounding the nipple 23 will assist the air pressure within the pipe 16 to unseat the 80 valve 24, this spring preventing any possible sticking of the valve. The air within the pipe 16 will then pass through the nipple 23 and into the pipe 18 whence it will be discharged through the flexible tube 18^a, 85 bore 42, and into the tire through the valve stem thereof, not shown. At the same time that the valve 45 is unseated from its seat 44 by the engagement of the valve plunger, not shown, with the 90 end of the stem 46, communication will be established between the bore 60 of the extension 50 and the nipple 61 connected with the hose 39. When the air within the tire reaches the predetermined pressure, the 95 portion of the air passing through the bore 60 of the extension 50 and the hose 38 will exert pressure within the housing 19 and will pass through the valve seat 35, resulting in upward movement of the stem 33 and compression of the spring 36. As the stem 33 rises its beveled end 37 will engage the trigger 32 and move the same laterally out of engagement with the teeth 31 whereupon the pressure of the spring 22 acting upon 100 the plunger head 21 will cause the rack bar 20 and plate 28 to spring back to original position, the plunger head 21 engaging the stem 25 of the valve 24 and forcing the valve 24 downwardly into engagement with 105 the upper end of the nipple 23, thus cutting off passage of air from the pipe 16. This downward movement of the bar 20 will cause partial rotation of the gear 15 and will consequently return the hand 14 to 110 its zero indicating or initial position. When the hand 14 is moved to indicate a low pressure, the bar 20, plate 28, and trigger 32 will be moved upwardly only a slight extent and the stem 33 in its upward movement will 115 disengage the trigger 32 from the teeth 31 much sooner than when the hand 14 is moved to indicate a high pressure, as will be apparent from a study of the disclosure.

In order to provide an alarm for warning the user when the valve 24 returns to closed position, we preferably provide upon the cover 11 at the zero end of the indicia thereon, a bell 40' which is so positioned that when downward movement of the bar 120

20 causes a partial rotation of the gear 15 and consequently return of the hand 14 to its initial or zero indicating position, it will be struck by the hand 14 and will give an 5 audible signal, making it known to the operator that the valve 24 is closed.

From the foregoing description and a study of the drawings, it will be apparent that we have thus provided a comparatively 10 simple and inexpensive device which will automatically supply to a tire a certain predetermined pressure and which will cease to supply further air pressure immediately upon the pressure within the tire reaching 15 the desired degree.

While we have shown and described the preferred embodiment of our invention, it is of course to be understood that we reserve the right to make such changes in the form, 20 construction, and arrangement of parts as will not depart from the spirit of the invention or the scope of the subjoined claims.

Having thus described our invention, we claim:—

25 1. A device of the character described comprising a casing, a compressed air pipe leading through said casing, a controlling valve within said casing normally preventing passage of air through said pipe, a 30 plunger normally engaging said valve for holding the same seated, means for moving said plunger a predetermined degree to permit opening of said valve, locking means for holding said plunger in adjusted position, 35 a housing adapted to be brought into communication with said air pipe, and a plunger movable within said housing under influence of air pressure therein, said last named plunger upon movement thereof, releasing said locking means.

2. A device of the character described comprising a casing, a compressed air conducting pipe extending through said casing, a control valve normally preventing 45 passage of air through said pipe, a spring pressed plunger normally engaging said valve for holding the same seated, manually operable means for moving said plunger a predetermined degree, a vertically slidable 50 plate carried by said plunger, a stationary ratchet bar within said casing, a trigger carried by said plate and engaging said ratchet bar for holding said plate and consequently said plunger in adjusted position,

and air pressure actuated means for releasing said trigger from engagement with said ratchet bar.

3. A device of the character described comprising a casing, a compressed air conducting pipe extending through said casing, a control valve normally preventing passage of air through said pipe, a spring pressed plunger normally holding said valve seated, manually operable means for moving said plunger a predetermined degree to permit unseating of said valve, a trigger member associated with the upper end of said plunger, a ratchet bar coöperating with and engaged by said trigger member for holding said plunger in adjusted position, 70 a housing communicating with said air pipe, a spring pressed plunger within said housing movable therein under the influence of compressed air, and the upper end of said last named plunger being adapted for 75 engagement with said trigger member whereby to disconnect the latter from engagement from said ratchet bar.

4. A device of the character described comprising a casing, a compressed air conducting pipe extending therethrough, a control valve normally preventing passage of air through said pipe, a vertically extending spring pressed plunger normally holding said valve seated and having its stem 80 formed as a rack, a manually movable gear meshing with said rack whereby said plunger may be elevated a predetermined degree to permit unseating of said valve, a plate carried by the upper end of said 85 plunger, a trigger carried by said plate, a vertically extending bar provided with ratchet teeth engaging said trigger for holding said plunger in adjusted position, a housing extending vertically upwardly from 90 and communicating with said pipe, a spring pressed plunger disposed within said housing and vertically movable upwardly under the influence of compressed air therein, and the upper end of said last named plunger 100 being inclined for engagement with said trigger whereby said trigger may be moved laterally out of engagement with said ratchet bar.

In testimony whereof we affix our signatures.

JAMES K. GREER.
CASKIE CURTRIGHT.
